(57) **CLAIM**

The ornamental design for an oven door protector, as shown and described.

DESCRIPTION

FIG. 1 is a perspective view of an oven door protector in accordance with the invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

That which is depicted in solid lines in the drawings represent the claimed invention and that which is depicted in broken lines forms no part of the claimed invention.
